UNITED STATES PATENT OFFICE.

HARRY N. COVELL, OF NEW YORK, N. Y.

OIL-BOX.

SPECIFICATION forming part of Letters Patent No. 635,665, dated October 24, 1899.

Application filed April 1, 1899. Serial No. 711,386. (No model.)

To all whom it may concern:

Be it known that I, HARRY N. COVELL, a citizen of the United States, and a resident of New York, (Brooklyn,) in the county of Kings 5 and State of New York, have invented certain new and useful Improvements in Oil-Boxes, of which the following is a specification.

This invention consists in an improvement on the construction shown in the Beekman 10 patent, No. 541,308, dated June 18, 1895, to which reference is hereby made for those parts of the apparatus not herein shown, the parts in the accompanying drawings being numbered to correspond with the parts shown in 15 the drawings of said patent.

In the accompanying drawings, Figure 1 is a vertical section of an apparatus containing my improvement. Fig. 2 is a horizontal section of the same, both sections being taken 20 through the center of the shaft.

The drum-shaft 7, pin 9, screw 11, collar 12, nut 13, bolt-receiving projections 14 and 15, disk 20, ring 21, top opening 19, disk 22, and opening 23 may all be constructed and combined as shown in said patent to Beekman. 25

24 is a web cast inside of the oil-box, so as to divide the oil-box into two compartments 25 and 26, extending from below the level of the friction-pin to a point above the same. 30 This web is preferably made of the L form shown, so as to project first horizontally from the disk 22 and then vertically, extending completely across and adjoining the ring 21 on opposite sides of the box. It is bored so 35 that the friction-pin passes through it, the junction between the friction-pin 9 and the

screw 11 being located in the compartment 26. In the compartment 25, next to the web-partition 24, around the friction-pin is placed the felt washer 27, backed by a washer of 40 thin sheet-iron 28, between which and the end of the shaft 7 is placed the spiral spring 29, so that the pressure of this spiral spring holds the felt washer 27 closely against the partition 24 around the friction-pin and prevents 45 oil from passing from the compartment 26 into the compartment 25. The compartment 24 is thus made substantially oil-retaining, as there is no opening from it excepting the hole closed by the friction-pin and the 50 threaded hole closed by the friction-screw 11 and the opening at the top through which it is filled.

The fact that in my oil-box the receptacle by which the oil is held around the joint between the screw and pin will not leak oil constitutes it a valuable improvement over that which is shown in said Beekman patent. 55

I claim—

In a rope-drum apparatus, in combination, 60 the drum-shaft 7, the pin 9 within said shaft, the screw 11 bearing against said pin, the nut 13, means whereby the same is secured on opposite sides of the end of the shaft, a box between said nut and said shaft and a partition 65 within said box whereby the oil is confined next to the end of the screw, substantially as described.

HARRY N. COVELL.
